UNITED STATES PATENT OFFICE.

FRANK A. SEBRING, OF SEBRING, OHIO.

DESIGN FOR A PLAQUE.

45,272.

Specification for Design.

Patented Feb. 17, 1914.

Application filed November 24, 1913. Serial No. 802,830. Term of patent 3½ years.

To all whom it may concern:

Be it known that I, FRANK A. SEBRING, a citizen of the United States, residing at Sebring, in the county of Mahoning and State of Ohio, have invented a new, original, and ornamental Design for Plaques, of which the following is a specification, reference being had to the accompanying drawing, forming part thereof.

In the drawings Figure 1 is a perspec-

tive view, and Fig. 2 is an end view of a plaque illustrating my new design.

I claim—

The ornamental design for a plaque as shown.

FRANK A. SEBRING.
